REVOLVING DOOR

Edmund Peremi, Manhasset, and Charles Kish, Elmhurst, N. Y., assignors to General Bronze Corporation, Long Island City, N. Y., a corporation of New York

Application November 18, 1933, Serial No. 698,570

13 Claims. (Cl. 20—18)

This invention relates to revolving doors of the type in which a plurality of leaves are normally held in fixed relation upon a rotary central support, but in which the leaves are foldably mounted on the support, and are adapted to fold in response to abnormal pressure occurring under panic conditions, or whenever it is desired to clear the doorway for any purpose.

10 The invention has for an object to provide mechanism for guiding and supporting the leaves in their folding movements and for defining movements of the leaves which are smooth and continuous in nature, there being no sudden shifting of rotational axes and hence no abrupt change of direction of the path of the portion of the leaf engaged by the operator.

15 It is a further object of the invention to provide controlling mechanism for attaining the above ends which is capable of firmly and positively controlling the leaves throughout their folding movements, and this without tolerating any point of exceptional weakness at which wobbling of the leaf is permitted or at which exceptional wear may occur.

20 It is a further object of the invention to provide improved means for detaining the leaves in their normal radial positions, the invention in this aspect being in the nature of an improvement upon the invention disclosed and claimed in the application of Edmund Peremi and Charles Kish, for Revolving doors, Serial No. 696,958 filed November 7, 1933.

25 One feature relating to the improved detent mechanism has to do with the provision of means for controlling the spring loading of the detent which is adapted to determine any one of a series of graduated maximum resistances, so that guess work as to the maximum spring loading and measurements to determine the actual spring loading are unnecessary.

30 Other objects and advantages will hereinafter appear.

In the drawings forming part of this specification,

35 Figure 1 is a secondary plan view illustrating a revolving door embodying the invention, the door being shown in dotted lines as folded and moved to one side of the doorway;

40 Figure 2 is a view in elevation of the door structure of Figure 1;

45 Figure 3 is a fragmentary, sectional, detail view taken on the section line 3—3 of Figure 5 looking in the direction of the arrows;

50 Figure 4 is a fragmentary, sectional, detail

view taken on the section line 4—4 of Figure 5 looking in the direction of the arrows;

55 Figure 5 is a fragmentary view in sectional elevation taken substantially along a diametrical plane that extends centrally of a pair of opposed leaves;

60 Figure 6 is a fragmentary plan view illustrating the inner ends of the leaves and the leaf guiding and retaining mechanism;

65 Figure 7 is a fragmentary perspective view illustrating the pivoted ends of the detent arms employed on the leaves; and

70 Figure 8 is a view generally similar to Figure 6 but illustrating the leaves in a folded condition.

The door 1 comprises a series of leaves 2 which are mounted upon a rotary central support 3 to turn within a doorway. The doorway comprises the usual arcuate guides 4, a floor 5 and a ceiling wall 6. The central rotary support includes a vertical shaft 7 which extends through the ceiling wall and is revolvably suspended from a trolley (not shown). The trolley is movable upon a track (not shown) to move the folded leaves to one side of the doorway into the position illustrated in dotted lines in Figure 1.

75 The vertical shaft 7 has fixed upon it a pair of discs 8, one located near the lower end of the shaft and the other near the upper end thereof. Sleeves 9 are disposed around the shaft above, below and between the discs 8. Each of the discs is formed to interact with cooperating elements on the leaves for supporting the leaves, for normally retaining the leaves in radial positions, and for guiding the leaves in their folding movements. The leaf carried members are 80 mounted in a hanger 10 which comprises complementary housing plates 11 and 12.

85 Each disc 8 is provided with a circular groove 13 which is common to all the leaves and cam grooves 15, for each leaf which come together in a socket 14. The grooves 15 cooperative with one door leaf curve outward in opposite directions from the socket 14 and communicate at their outer extremities with groove 15 for controlling adjacent leaves. In radial alignment 90 with each of the sockets 14 provision is made of a guide pin or projection 16.

95 Each hanger 10 has fixed upon it a guide pin 17 which is normally seated in the base of one of the sockets 14 and which may travel along 100 and be guided by the socket walls and the grooves 15. Each hanger 11 is also provided with an outer pin 18 having an arcuate shoe 19 pivoted thereon. The shoe 19 fits in the groove 13 and is guided by said groove so that 110

the pin 18 is constrained to move in a circular path.

Each hanger also includes a cam 20 which is ovate in form. The lesser dimension of the 5 cam is disposed width-wise of the door leaf by which it is carried and is entirely confined within the normal lateral bounds of the leaf. The cam 20 bears against one of the pins 16 of the disc 8 in the normal position of the leaf, and 10 the cam is of such contour and dimensions in relation to the configurations and dimensions of the guide grooves 13 and 15 and the socket 14 that the cam is caused to travel in engagement with the guide pin 16 from the beginning of a 15 folding movement until after the pin 17 has fully entered one of the grooves 15. The hanger is also provided with a guiding surface 21 which bears against the outer side of the pin 16 until the hanger has cleared the pin.

20 The provision of the cam 20 is particularly important for the reason that the cam 20 and the pin 16 afford support for positively guiding the door movement at the time when the pin 17 is passing over from the socket 14 into one of 25 the grooves 15, at which time the pin 17 is not so completely supported as in the other stages of the folding movement. The folding movement may be terminated when a leaf has been folded to a position 2a or 2b illustrated in Figure 8, namely 45° from normal, but any one of 30 the leaves may be folded further to a position such as illustrated at 2c or 2d in Figure 8, namely 135° removed from normal.

The grooves 15 for controlling adjacent leaves 35 communicate with one another so that the pins 17 of adjacent leaves may have freedom to travel to a common point at the common extremity of two such communicating branch grooves. The limit of movement, however, is reached simultaneously with the arrival of the pin 17 in such 40 position. Each pin 16 is so located with reference to the center of the shaft 7 that it is adapted to serve as a positive stop for preventing movement of either leaf adjacent the leaf 45 which it is designed to control, beyond a position 135° displaced from normal.

In accordance with one feature of the present invention, provision is made of improved detent means for normally retaining the leaves in 50 radial positions. This detent means follows generally the principle and construction of the detent means illustrated and claimed in pending application Serial No. 696,958 hereinbefore referred to.

55 Each leaf carries a detent including angularly related arms 22 and 23 which are pivoted at their outer ends upon a vertical pivot pin 24 mounted in a slide 25. The arms 22 and 23 have ears 26 and 27, respectively, which are mounted, one below, the other above, upon the pivot pin 24. A light spring 28 is received within a bore 29 at the outer end of the slide 25 and bears against an abutment shoulder 30 fixed on the lower hanger plate 12. The slide is provided 60 with a beveled face 31 at the upper outer corner thereof, which engages a beveled face 32 at the forward end of a lever 33. The lever 33 is fulcrumed upon a transverse pin 34, and the outer end of the lever bears normally against a 65 stop 35 fixed on the upper housing plate 11, being held thereagainst by a plunger 36.

70 The plunger 36 has a stem portion which is slidably mounted in a bore 37 formed in a carrier 38. A spring 39 surrounds the plunger and urges it upward, bearing at its upper end

against the head of the plunger and at its lower end in the base of an annular groove 40 which is formed in the carrier 38. The carrier 38 is arranged to be moved longitudinally of the lever 33 to carry the plunger 36 toward and 80 from the fulcrum of the lever 33 to vary the effectiveness of the spring in resisting the outward thrust of the slide 25. For this purpose, the carrier 38 has a rack bar 41 secured upon it, and a pinion 42 is provided for operating the 85 rack bar. The pinion shaft 43 has a square opening 44 formed in it which is accessible from the exterior of the door leaf and which may be operated by the insertion therein of a square key.

90 Statutes and ordinances in various jurisdictions specify maximum limits of resistance to folding which may not be exceeded. These limits vary, however, for different jurisdictions, so that it is desirable to provide a construction in 95 which the maximum resistance to folding may be adjusted to any one of a series of predetermined values.

To this end provision is made on the carrier 38 of a plate 45 having a stop member 46 projecting from one face thereof. The plate 45 is provided with a pair of screw holes 47 through which attaching screws 48 may be passed. The carrier 38 is provided with a series of threaded openings 49 adapted to be used selectively in 100 pairs to effect securing of the plate 45 to the carrier in predetermined positions.

With the setting illustrated in Figure 5 the spring 39 applies the highest maximum resistance for which the mechanism can be set. With 110 this setting the plunger 36 may be moved by operation of the pinion 42 to a position directly beneath the fulcrum of the lever 33 to render the spring 39 wholly ineffective to resist folding movements. When it is desired to restore the 115 initial effectiveness of the spring, the pinion 42 is simply operated in the opposite direction until the stop member 46 engages an arresting member 50 fixed on the lower housing plate 12. A bullet 120 catch 51 engageable with a recess in the lower face of the plate 45 yieldingly retains the carrier in this outer position.

Should the door be intended for use in a jurisdiction where the maximum resistance to folding is of a lower value than that for which the parts are set in the Figure 5 position, the plate 45 will not be attached to the carrier 38 in the position illustrated, but a pair of the holes 49 appropriate to the situation will be utilized for the reception of the screws 48. In this case 130 the stop member 46 and the arresting member 50 will be in engagement to prevent outward movement of the carrier 38 when the plunger 36 is located nearer to the fulcrum of the lever 33 than the position illustrated in Figure 5. As 135 before, however, the pinion 42 may be operated to move the plunger into alignment with the fulcrum of the lever 33 and to return it to its original position. When such original position is restored the bullet catch 51 will, as before, be 140 effective to prevent unintended shifting of the carrier 38.

Each of the arms 22 and 23, together with the slide block 25, forms a toggle for resisting folding movement of a leaf in one direction. The toggle 145 22, 25 requires to be straightened in order to permit movement of the leaf counterclockwise and the toggle 23, 25 requires to be straightened in order to permit movement of the leaf clockwise. The ends of the arms 22 and 23 engage, 150

respectively, in notches 52 and 53 formed in the periphery of the disc 8. The arm of the toggle which is straightened in a folding movement ceases to resist folding as soon as the dead center position of the toggle is crossed, and such arm rides thereafter upon the periphery of the disc. It will be observed from an inspection of the 5 detent carried by the leaf illustrated at 2d in Figure 8 that the toggle arm 23 has traveled over the notch 52 which is provided for normally 10 detaining the arm 23 of an adjacent leaf. It is not desired that the arm 23 engage in this notch on the return movement. The periphery of the disc 8 is accordingly provided with a hump or 15 projection 54 for guiding the arm 23 clear of such notch 52. It is desired, however, to assure that the arm 23 will enter the notch 53 by which it is intended normally to be detained. Each hump or projection 54 is extended therefore 20 for the full distance between the paired notches 52 and 53 and provided with beveled ends leading into the notches. It is apparent, of course, that each hump acts in the same way regardless of the direction in which the leaves 25 are swung, the arrangement being such that any pair of adjacent leaves may be swung toward one another into parallel positions such as 2a and 2b, and the remaining leaves may be swung through 135° each, in opposite directions, to positions 30 like those indicated at 2c and 2d.

While we have illustrated and described in detail certain preferred forms of our invention, it is to be understood that changes may be made therein and the invention embodied in other structures. We do not, therefore, desire to limit 35 ourselves to the specific construction illustrated, but intend to cover our invention broadly in whatever form its principle may be utilized.

We claim:

1. In a revolving door in combination, a rotary 40 central support, leaves foldably mounted on the support, and means holding the leaves to the support and positively guiding them in their folding movements in opposite directions comprising a cam disc on the support having a continuous annular groove, a socket for each leaf, outwardly extending cam grooves extending divergently from each socket, and a stationary 45 guiding projection for each leaf, each leaf having a pair of guide elements for cooperating, respectively, with the annular groove and with the cam grooves, and a cam having bearing engagement with the guiding projection on the disc.

2. In a revolving door, in combination, a 50 rotary central support, leaves foldably mounted on the support, and means holding the leaves to the support and positively guiding them in their folding movement in opposite directions comprising a cam disc on the support having an annular groove common to all leaves, a socket for each leaf, and outwardly extending cam 55 grooves extending divergently from each socket, and a pair of guide elements on each leaf for cooperating, respectively, with the annular 60 grooves and with the cam grooves.

3. In a revolving door, in combination, a 65 rotary central support, leaves foldably mounted on the support, and means holding the leaves to the support and positively guiding them in their folding movements in opposite directions comprising a cam disc on the support having a continuous annular groove, a socket for each leaf, outwardly extending cam grooves extending 70 divergently from each socket, and a stationary 75 guiding projection for each leaf, each leaf

having a pair of guide elements for cooperating respectively, with the annular and cam grooves, and a cam having bearing engagement with the guiding projection on the disc, the leaf carried cam being so shaped with respect to the configurations of the grooves in the disc that it is caused to travel in contact with the guiding projection on the disc at the time when the guide element, cooperative with the cam grooves, passes from the socket into one of the cam 80 grooves.

4. In a revolving door in combination, a rotary central support, leaves foldably mounted on the support, and means holding the leaves to the support and positively guiding them in their 85 folding movements in opposite directions comprising a cam disc on the support having a continuous annular groove, a socket for each leaf, outwardly extending cam grooves extending divergently from each socket, and a stationary 90 guiding projection in radial alignment with each socket, and each leaf having a pair of guide elements for cooperating respectively with the annular and cam grooves, and a cam having bearing engagement with the guiding projection 95 in the normal radial position of the leaf and throughout the folding movement in either direction until after the guide element, cooperative with the socket has fully entered one of the cam grooves.

5. In a revolving door in combination, a rotary central support, leaves foldably mounted on the support, and means holding the leaves to the support and positively guiding them in their 100 folding movements in opposite directions comprising a cam disc on the support having a continuous annular groove, a socket for each leaf, outwardly extending cam grooves extending divergently from each socket, and a stationary 105 guiding projection in radial alignment with each cam socket and each leaf having a pair of guide elements for cooperating respectively with the annular and radial grooves, and a cam having bearing engagement with the guiding projection 110 in the normal radial position of the leaf and throughout the folding movement in either direction until after the guide element, cooperative with the cam grooves has fully entered one of the cam 115 grooves, each guiding projection being so located with reference to the axis of the central support and the configurations and dimensions of the other leaf guiding means, that it is adapted to serve as a stop for limiting swinging of either leaf, adjacent the one controlled by it, to a position substantially 135° removed from 120 normal.

6. In a revolving door, in combination, a rotary central support, leaves foldably mounted on the support, and means holding the leaves to the support and positively guiding them in their 125 folding movements in opposite directions comprising a cam disc on the support having a continuous annular groove, a socket, for each leaf, outwardly extending radial grooves extending divergently from each socket, and a stationary 130 guiding projection in radial alignment with each socket, and each leaf having a pair of guide elements for cooperating respectively with the annular and cam grooves, and a cam having bearing engagement with the guiding projection in 135 the normal radial position of the leaf and throughout the folding movement in either direction until after the guide element cooperative with the cam grooves has fully entered one 140 of the cam grooves, said leaf carried cam being 145

ovate in form and having its lesser dimension disposed widthwise of the leaf.

7. In a revolving door, in combination, a rotary central support, leaves foldably mounted on the

support, and means holding the leaves to the support and positively guiding them in their folding movements in opposite directions comprising a cam disc on the support having a continuous annular groove, a socket for each leaf,

18 outwardly extending cam grooves extending divergently from each socket, and a stationary guiding projection in radial alignment with each socket, and each leaf having a pair of guide elements for cooperating respectively with the an-

15 nular and cam grooves, and a cam having bearing engagement with the guiding projection in the normal radial position of the leaf and throughout the folding movement in either direction until after the guide element, cooperative

20 with the cam grooves, has fully entered one of the cam grooves, said leaf carried cam being ovate in form and having its lesser dimension disposed widthwise of the leaf, and lying wholly within the normal lateral bounds of the leaf.

25 8. In a revolving door, in combination, a rotary central support, leaves foldably mounted on the support, and means holding the leaves to the support and positively guiding them in their folding movements in opposite directions com-

30 prising a cam disc on the support having a continuous annular groove, a socket for each leaf, outwardly extending cam grooves extending divergently from each socket, and a stationary guiding projection in radial alignment with each

35 socket, and each leaf having a pair of guide elements for cooperating respectively with the an- nular and cam grooves, and a cam having bearing engagement with the guiding projection on the disc, the cam grooves being symmetrically

40 disposed with relation to the guiding projection, and the cam on the door leaf being symmetrical- ly formed and disposed with relation to the cen- tral plane of the leaf.

9. In a revolving door, in combination, a rotary central support, leaves foldably mounted on the support, and means holding the leaves to the support and positively guiding them in their folding movements in opposite directions comprising a cam disc on the support having an an-

50 nular groove common to all leaves and two cam grooves for each leaf extending divergently, the outer extremities of the cam grooves for adja- cent leaves being in communication with one an- other, and a pair of guide elements on each leaf

55 for cooperating, respectively, with said grooves.

10. In a revolving door, in combination, a rotary central support, leaves foldably mounted on the support, and means holding the leaves to the support and positively guiding them in their folding movements in opposite directions comprising a cam disc on the support having an an-

60 nular groove common to all leaves and two out- wardly extending cam grooves for each leaf ex- tends in opposite directions from a common

65

point, all of the cam grooves being disposed in- side, and clear of, the annular groove, and a pair of guide elements on each leaf for cooperating, respectively, with said annular and cam grooves.

11. In a revolving door, in combination, a ro- tary central support, leaves foldably mounted on

80

the support, and means normally retaining the leaves in radial positions comprising in each in-

85

stance an abutment device on the central sup- port, a detent normally engaging the abutment

90

device, a spring for urging the detent to engag- ing position, a spring carrier operable to move the spring to alter the effect thereof upon the de-

95

tent, a stop member on the spring carrier, and an arresting member secured on a fixed part of

100

the door leaf and cooperative with the stop mem- ber to define a fixed limit of movement of the carrier in a direction to increase the effective- ness of the spring, and cooperating means on the

105

carrier and the stop member mechanically de- termining a plurality of positions of attachment

110

of the stop member to the carrier, each to pro- vide a predetermined maximum effectiveness of

115

the spring.

12. In a revolving door, in combination, a ro- tary central support, leaves foldably mounted on

120

the support, and means normally retaining the leaves in radial positions comprising in each in-

125

stance an abutment device on the central sup- port, a detent normally engaging the abutment

130

device, a spring for urging the detent to engag- ing position, a spring carrier operable to move the

135

spring to alter the effect thereof upon the detent, a stop member on the spring carrier, a stop

140

member on a fixed part of the door leaf and co- operative with the stop member on the spring car- rier to define a fixed limit of movement of the

145

carrier in a direction to increase the effec- tiveness of the spring, and means for remount- ing and relocating one of said stop members in

150

a new mechanically determined position to pro- vide another predetermined limit of effectiveness of the spring.

13. In a revolving door, in combination, a ro- tary central support, leaves foldably mounted on

120

the support, and means for retaining the leaves in their normal positions with relation to the central support comprising a disc on the central sup- port and a detent on each leaf including a pair of alternatively effective toggles, each tog-

125

gle including a disc engaging arm and requiring to be straightened in order to permit the door to be folded in one direction, the inner disc engag- ing ends of the disc engaging arms being normally spread apart, and the disc having spaced

130

notches for receiving the respective arms and be- ing provided with a projection between the notches of each pair to guide the toggle arms of adjacent leaves clear of the associated notches and to assist in directing the toggle arms of the

135

associated leaf into the notches with which they are intended to cooperate.
